UNITED STATES PATENT OFFICE.

THEODORE C. ERPENBECK, OF CHICAGO, ILLINOIS.

BELT BUCKLE.

Application filed February 21, 1922. Serial No. 538,314.

To all whom it may concern:

Be it known that I, THEODORE C. ERPENBECK, a citizen of the United States, residing at the city of Chicago, in the county of Cook 5 and State of Illinois, have invented certain new and useful Improvements in Belt Buckles, of which the following is a specification.

My invention relates to buckles for fastening the belts usually employed to support the trousers and the like use, and the special object of the present invention is to not only provide a buckle which will fasten said belt, but one in which the front or exposed portion is made from a separate piece 10 of metal or other material, and which may therefore be of much lighter material, and will therefore be less expensive and may be cut or stamped with the desired monogram 15 or other ornamentation desired at less expense than the thicker metal.

Another object is to provide such a buckle in which the separate front part having the monogram or ornamentation may be easily 20 and quickly disengaged and replaced by a front with some other desired monogram or design.

Another object is to provide a perforated plate firmly attached to one end of the belt, 25 with a second plate adjustably attached to the belt at or near the reverse end, said second plate having suitably extending posts for engaging the perforations in the first 30 plate, and a front plate readily attachable to said second plate.

With the foregoing and other objects in view which are specifically set forth in the annexed specification, my invention consists of the parts and arrangements as hereinafter 35 described and claimed, and while I do not wish to be restricted to the exact details of construction shown herein, yet, for the purpose of illustrating a particular embodiment thereof, reference is had to the accompanying drawings, in which like reference characters designate the same parts throughout the several views, and in which,

Figure 1 is a front plan view of one of my belt buckles, part of the front being broken away to disclose the rear plate.

Figure 2 is a cross section along the line 1-1 of Figure 1.

Figure 3 is a detail view of the plate 5 showing the posts for engaging the belt and 55 the plate 2.

Figure 4 is a detail view of the front plate

with portions of the sides broken away to show the curved edge.

Figure 5 is a longitudinal section along the line 2-2 of Figure 1. 60

Figure 6 is a view showing the perforated plate attached to the belt.

Figure 7 is a detail view of the perforated plate separate from the belt.

In the accompanying drawings showing a belt of the usual type with one of my improved buckles attached thereto, 1 represents the belt, and 2 a perforated plate attached by means of rivets as 3 at one end of said belt. At 4, 4 are shown the perforations employed by me to receive the posts of the plate 5 for attaching the ends of the belt together. The plate 2 is preferably made of sheet metal, punched or stamped as desired, and the plate 5 is also preferably made from sheet metal punched or stamped as desired. 70 The posts 6, 6 shown extending rearwardly from the plate 5 are formed of separate material, attached to said plate by solder or riveting. I have preferably made the plate 80 5 with the opening 8 in its middle portion, to reduce the weight, and cost by reducing the amount of material required. At the edges of the plate 5 and near the four corners, I have formed the ears 9, 9, 9, 9, which 85 are positioned and designed to engage the indentations 10, 10, 10, 10 formed in the front plate 11 for the express purpose of engagement therewith, to lock said front plate in engagement with said plate 5 whenever it is placed upon said plate 5 with the 90 indentations 10 in engagement with said ears 9.

The front plate 11 is preferably made of a better material than the other portions, 95 and as there is no strain upon any portion of it, it may be made of very light material thereby reducing the expense of the materials required, and also providing a thin metal which is cut or stamped with the desired monogram or other design or ornamentation at less expense than a heavier metal could be manufactured. 100

My buckle is easily and quickly assembled as follows: Attach the plate 2 at one end 105 of the belt, as shown, then slide the front plate 11 upon the plate 5 until the indentations 10 engage the ears 9 of plate 5. The posts 6, 6 are then engaged in the perforations 1', 1' of the belt, thereby attaching said 110 plates 5 and 11 to said belt. The belt is then placed about the waist, and the posts

6, 6 of the plate 5 engaged in the perforations 4, 4 of the plate 2, attaching the reverse ends of the belt together as desired.

By this construction the plates 2 and 5 may be made of any suitable material of low cost, and may be made up in stock quantities, and the desired front plates may be supplied and attached from time to time as the buckles are sold. Also, it will be seen 10 that the front plate may be easily and quickly removed, and another of different design or monogram substituted in its place in an instant, without changing any other portion of the buckle or belt and without 15 loss or waste of any kind.

Having thus described my said invention, what I claim and desire to secure by Letters Patent, is the following:—

1. In a device of the class described, the 20 combination of a perforated plate attached to one end of a belt, a second plate having posts thereon for engagement with said belt and the perforations in said first named plate and a front plate adapted for engagement with said second named plate.

2. The combination with a belt of a perforated plate attached thereto, a second plate having curved posts or hooks for engaging perforations in the belt and in said first 30 named plate, and a front plate having curved edges for engaging the edges of said second named plate.

3. In a buckle for belts and the like, the

combination of a perforated plate for attachment to one end of the belt, of a second 35 plate for adjustable attachment to the reverse end of the belt, said second plate having projections at its edges, and a front plate having indentations adapted to engage the said projections on the second named 40 plate.

4. A belt buckle consisting of three plates, one having spaced openings therein, a second having spaced curved posts thereon, and means at its edges for engaging co-acting 45 means provided in the third plate for engaging and retaining said third plate in engagement therewith.

5. In a device of the class described, the 50 combination of a plate having spaced openings therein, of a second plate having suitably spaced posts for engaging said spaced openings in said first named plate, and a third cover plate for covering and concealing both of said plates, and indentations in 55 one of said plates for engaging suitable projections in another for retaining said cover plate in engagement with said plates.

In testimony whereof, I have hereunto set my hand in the presence of two subscribing 60 witnesses.

THEODORE C. ERPENBECK.
